UNITED STATES PATENT OFFICE.

BENJAMIN WALTERS, OF BUNOLA, PENNSYLVANIA.

BURGLAR-PROOF SAFE.

No. 893,288.

Specification of Letters Patent.

Patented July 14, 1908.

Application filed April 21, 1905. Serial No. 256,725.

To all whom it may concern:

Be it known that I, BENJAMIN WALTERS, a citizen of the United States, residing at Bunola, in the county of Allegheny and the 5 State of Pennsylvania, have invented a new and useful Improvement in Burglar-Proof Safes, of which the following is a specification.

This invention relates to the burglar proof safe, and especially to the construction of the 10 walls of the safe. The object being a wall through which it will be impossible to drive a drill, and also to provide means to prevent the insertion of explosives for the purpose of destroying a part of the wall opposing the 15 progress of the drill.

The invention consists of the novel features of construction and combination of parts hereinafter described, pointed out in 20 the claims, and shown in the accompanying drawings, in which,

Figure 1 represents a safe having a part of one wall broken out and shown partly in section. Fig. 2 is a transverse section through the wall of the safe. Fig. 3 is a perspective 25 view of a part of an inner steel plate.

In these drawings A represents an outer wall of hard steel, and B represents an inner wall also of hard steel, and spaced from the wall A. The wall B has formed upon its face 30 opposing the wall A, a plurality of laterally extending pointed spurs B' pyramidal in form, the bases of said spurs contacting and their apices extending into the space formed between the wall B and the wall A. A pack- 35 ing of soft rubber C is placed against the in-

ner faces of the wall A, and contacts with the points of the spurs or projections B', between the points B' a packing of waste is inserted.

In a safe having a wall constructed in this manner a drill after passing through the 40 plate A will travel some distance through the soft rubber, and the waste where it will have more or less play, and will not be held closely to a direct line of advance, and when the point of the drill contacts with the hard and 45 polished sides of the spurs, the point of the drill will slip, and if the drill is forced farther the point will catch in the angle between the spurs and be broken. When the drill is withdrawn the packing D and the soft rubber C 50 will close behind the drill point and the closing of the passage through the rubber and waste made by the drill will prevent the insertion of an explosive for the purpose of blowing off one or more of the spurs B'. 55

Having thus fully described my invention, what I desire to secure by Letters Patent is:—

A safe comprising inner and outer walls, of metal, pyramidal spurs carried by said inner wall, a packing of elastic material arranged 60 between the walls and against the inner face of the outer wall, the points of said spurs projecting into the elastic material and a packing material placed between the spurs, as set forth.

BENJAMIN WALTERS.
